FIG. 4.

INVENTOR :
Frederick Maussner
BY F. DeWitt Goodwin,
ATTORNEY

UNITED STATES PATENT OFFICE.

FREDERICK MAUSSNER, OF COLLINGSWOOD, NEW JERSEY, ASSIGNOR TO HENRY WILHELM COMPANY, OF PITTSBURGH, PENNSYLVANIA.

FILLING FOR MATTRESSES.

1,400,302.

Specification of Letters Patent. Patented Dec. 13, 1921.

Application filed May 27, 1920. Serial No. 384,561.

To all whom it may concern.

Be it known that I, FREDERICK MAUSSNER, a citizen of Germany, residing at Collingswood, in the county of Camden and State of New Jersey, United States of America, have invented certain new and useful Improvements in Fillings for Mattresses, of which the following is a specification.

My invention relates to improvements in mattresses and particularly relates to a filling for mattresses formed of interlaced fibrous material.

The object of this invention is to form a mattress which will retain its shape and uniformity of thickness. This object I accomplish by forming the mattress of two or more layers of material, each layer being securely held against any disarrangement of the material composing said layers, by first interlacing the loose fibrous material upon a sheet of woven fabric, such as burlap, thereby forming a comparatively thin bulk of the fibrous material which can be effectively held upon the sheet of fabric, so that it will not slip out of place or become tufted. Then by placing two or more of the said layers of material thus formed, one on top of the other, a filling is formed which may be readily inserted into a ticking or casing to complete the mattress.

Heretofore fillings for mattresses have been constructed by placing the layers loosely one on top of the other and securing the entire bulk together by stitching or interlacing. This construction, depending entirely upon the stitching for holding the material together, has the disadvantage of allowing the material to become tufted or to shift out of position, due to the thickness of the entire bulk at the points where the long stitching passes through the mattress.

Referring to the accompanying drawing; Figure 1, is a perspective view of a mattress constructed in accordance with my invention; Fig. 2, is a vertical section, drawn on a larger scale, showing one layer of fibrous material interlaced upon a sheet of fabric; Fig. 3, is a vertical section of a portion of the filling shown in Fig. 1; and Fig. 4, is a vertical section of a filling for mattresses comprising several layers of fibrous material secured on fabric and the bulk secured together by interlacing.

In the accompanying drawings, in which like reference characters refer to like parts,

1 represents the mattress filling adapted to be incased in a ticking 2, into which it may be readily inserted, or removed therefrom, for the purpose of cleaning and airing.

The bulk of material forming the filling 1 60 comprises two or more layers of fibrous material 4 such as curled hair or moss, which is secured upon a sheet of woven fabric 5, such as burlap. The fibrous material 4 is secured to the burlap 5, as shown in Fig. 2, 65 by the well known method of interlacing, consisting of forcing, or pulling the fibrous material through the burlap by barbed needles, so that the fibrous material is securely fastened upon the burlap and will retain its 70 formation and uniform thickness.

The filling for mattresses, constructed in accordance with my invention, consists of two or more layers, 6 and 7, of the fibrous material, first secured on the burlap 5, and 75 laid, one layer on top of the other, preferably with the sheets of fabric 5, adjacent to each other, and said layers secured together by stitching or tying with thread, as shown at 8, in Figs. 1 and 3, or by interlacing the 80 fibrous material through the entire bulk, as shown at 9, in Fig. 4.

The layers of material 6 and 7, when formed, as shown in Fig. 2, with the fibrous material projecting through the burlap will 85 present an uneven surface, so that two layers laid together with the sheets of burlap adjacent to each other, will adhere together sufficiently to retain the shape of the mattress, when incased in the ticking 2. Therefore, in thin or light weight mattresses, it is not essential that the layers be secured together by stitching or interlacing as above described; but in thick, heavy mattresses especially when formed of more than two layers, as shown in Fig. 4, it is desirable to secure the layers together to prevent the material from shifting out of its proper position. Said layers may be secured together with cement, or glue, or by the use of any 100 suitable adhesive material, without departing from my invention.

Having thus described my invention, I claim and desire to secure by Letters Patent:

1. A filling for mattresses comprising layers of filling material, a sheet of fabric secured to each of said layers of material and means for securing the layers of filling material and said sheets of fabric together to 110

form a bulk of material of sufficient thickness to form a filling for a mattress.

2. A filling for mattresses comprising layers of fibrous material, a sheet of fabric secured to each layer of the fibrous material and said layers of fibrous material and said sheets of fabric secured together by inter-

lacing the fibrous material of one of the said layers through the fabric and into another one of the layers to form a bulk of material 10 of sufficient thickness to form a filling for a mattress.

In testimony whereof I affix my signature.
FREDERICK MAUSSNER.
